DOMESTIC APPLIANCE

Francis H. McCormick, Dayton, Ohio, assignor to General Motors Corporation, Detroit, Mich., a corporation of Delaware

Continuation of application Serial No. 217,618, March 26, 1951. This application June 15, 1953, Serial No. 361,717

1 Claim. (Cl. 34—60)

This invention relates to domestic appliances and particularly to apparatus for drying damp fabrics such as clothes and other articles.

This invention is a continuation of my copending application, Serial No. 217,618, filed March 26, 1951, now abandoned.

An object of this invention is to provide a clothes dryer of the rotating drum type with an electric lamp within the drum at one end in a manner to avoid interference with the loading and unloading of clothes through a door opening at the other end.

Other objects and advantages will become apparent from the following description taken with the accompanying drawings in which:

Fig. 1 is a vertical sectional view of my improved clothes dryer taken on the line 1—1 of Fig. 2;

Fig. 2 is a transverse vertical sectional view of the clothes dryer taken on the line 2—2 of Fig. 1;

Fig. 3 is a horizontal sectional view taken on the line 3—3 of Fig. 2 showing the lower portion of the clothes dryer;

Fig. 4 is a fragmentary vertical sectional view taken on the line 4—4 of Fig. 3 showing a condenser and moisture trap arrangement located within the clothes dryer cabinet;

Fig. 5 is an enlarged fragmentary sectional view showing a drain pan partially removed from the dryer cabinet;

Fig. 6 is an enlarged fragmentary sectional view similar to Fig. 5 with the drain pan omitted and showing the condenser partially removed from the dryer cabinet;

Fig. 7 is an enlarged fragmentary sectional view showing the circulation of drying air over bodies of water contained in trays disposed below a heat exchanger located in the dryer cabinet.

Referring to the drawings, for illustrating the present apparatus or clothes dryer, I have shown in Fig. 1 thereof a cabinet comprising an outer stationary casing including a front sheet metal wall 11, a sheet metal base 12, a sheet metal rear wall 14, a sheet metal top wall 16 having the raised back plate 17 and side walls (see Figs. 2 and 3) 18 and 19. The front wall 11 and side walls 18 and 19 are integral with one another and are of the wrap-around type wherein the ends of the sheet metal are flanged inwardly at the rear of the cabinet to provide a mounting for removably securing back plate 14 to the cabinet (see Fig. 3). The base 12 may be permanently attached to the front wall 11 and side walls 18 and 19 in any suitable manner preferably by being welded thereto. Top wall 16 of the cabinet may be removably secured to the front and side walls 11, 18 and 19 respectively, in any desired or well-known manner to complete the outer box-like casing. The dryer cabinet also includes a stationary inner casing composed of a sheet metal back wall 21 (see Fig. 1), a U-shaped sheet metal wall 22 (see Fig. 2), a front sheet metal wall 23 (see Fig. 1) and a top sheet metal wall 24 placed over and suitably secured to the upper edge of the walls 21, 22, and 23. This inner casing may be substantially surrounded with any suitable or desirable

2

insulating material as is conventional in the art. Front wall 11 of the outer casing is provided with an opening normally closed by a door 26. This door 26 also normally closes a flanged opening 27 provided in a front panel 28 secured, by screws or the like 29, to the front wall 23 of the inner casing adjacent an opening therein (see Fig. 1). An opening 31 (see Fig. 2) in the bottom of the U-shaped wall 22 of the inner casing affords communication between the interior of the inner casing and the interior of the outer casing for a purpose to be hereinafter described.

A damp clothes receiving container or drum is rotatably located within the walls of the stationary inner casing. The container or drum includes a cylindrical sheet metal wall 34 (see Fig. 2) having a plurality of holes or perforations 36 therethrough (see Fig. 1) and a front and back wall 37 and 38 respectively. Cylindrical wall 34 of the drum is provided with integrally formed and inwardly directed vanes or drag members 39. Front wall 37 of the container or drum is provided with a round opening bounded by a flange 41 (see Fig. 1) which surrounds the flange of opening 27 in front panel 28. Three rollers 42, two of which are shown in Fig. 1 of the drawings, are equally spaced apart around the opening bounded by flange 41 and are secured to the front panel 28 in any suitable or desirable manner such as by the brackets 43. Rollers 42 bear against and roll along the surface of flange 41 to support the front portion of the clothes container or drum and permit the same to be rotated about a horizontal axis. The provision of the rollers 42 supporting the weight of the front portion of the clothes dryer drum forms no part of the present invention. The axis of rotation of the clothes drum is formed by a hub in the back thereof as is conventional in the art. This hub may include a hollow shaft 44 suitably attached to the back wall 38 of the drum and extending through a bearing suitably mounted upon wall 21 of the inner cabinet casing. An electric illuminating lamp bulb 46 and an electric ozone producing device or bulb 47 are located in the clothes drum and are mounted upon suitable brackets carried by the hollow shaft 44 or by the rear wall 38 of the drum. A protective guard cap 49 is disposed over bulbs 46 and 47 and is attached to the drum rear wall 38 by screws or other attaching means. Cap 49 may be a perforated metal member or it may, if desired, be formed of a transparent plastic or the like material.

The support for the lamp 47, which passes through the hollow shaft 44, includes the necessary electrical connections for energizing the lamp, which connections lead to the outside of the outer casing. The lamp 46 preferably is held stationary within the drum. The shaft 44 of the hub of the clothes drum has a large pulley wheel 51 keyed thereto, and a belt 52 surrounding this pulley extends around a smaller pulley 53 mounted on a short shaft 55 which may be rotatably secured to a spring-pressed movable bracket (not shown) carried on the back wall 21 of the inner stationary casing. This short shaft also carries a large pulley 54 having a belt 55 thereon which belt extends over another small pulley 56. Pulley 56 is keyed to a drive shaft extension 57 which passes through the rear wall 21 of the inner casing and is connected to the shaft of an electric driving motor 58 located in the dryer cabinet in the space between the inner and outer stationary casings thereof. The motor 58, when energized, rotates shaft 57, small pulley 56, pulley 54, through the belt connection 55, small pulley 53 and pulley wheel 51 through the belt connection 52. Rotation of pulley wheel 51 through a conventional speed reducing means of the type described rotates the hollow shaft 44, at the hub of the clothes drum, and also the clothes drum itself within the inner stationary casing of the cabinet. This speed reducing drive for the clothes drum is conventional and

may, if desired, be of the type shown and described in the patent to James R. Moore, No. 2,385,223 dated September 18, 1945.

Electric heaters 61 and 62 (see Fig. 2) are mounted on arcuate shaped, in cross-section, reflectors or the like 63 which are carried by a plate 64 removably attached at one side of the upper portion of back wall 21 of the inner casing. These heaters 61 and 62 extend inwardly of wall 21 over a substantial portion of the rotatable clothes drum and are connected to a source of electric supply through any suitable manually set time or chronometric switch means (not shown).

A plurality of holes 60 may be provided in plate 64 or, if desired, in the upper portion of rear wall 21 of the inner casing (see Fig. 2). These holes 60 serve to permit air from exteriorly of the outer casing to enter the inner casing above the heaters 61 and 62. Air passing through the holes 60 may enter the space between the inner and outer casings by way of an opening or openings 65 (see Fig. 1) provided at the top of rear wall 14 of the outer casing in the vicinity of the holes 60. In addition to the stationary inner and outer main casings of the dryer cabinet, I provide in the lower portion thereof sheet metal baffle members 66 and 67 (see Fig. 2), which aid in supporting the U-shaped metal wall 22 of the inner casing, having leg portions 68 and 69 respectively resting on the cabinet base 12. The baffle members 66 and 67 are spaced from front wall 11 of the cabinet and extend rearwardly where they are secured to back wall 21 of the inner casing (see Fig. 3). Spaced apart sheet metal cap members 71 and 72 are secured to the front edges of baffles 66 and 67 respectively. The cap member 72 has an opening 73 therein in which is disposed a blower or fan 74 mounted on the shaft of motor 58. The space between the cap members 71 and 72 is below the opening 31 in the bottom of U-shaped wall 22 of the inner casing and is in horizontal alignment with an opening 75 (see Figs. 3, 5 and 6) in the lower portion of the front wall 11 of the dryer cabinet located intermediate two louvered or the like openings 76 and 77 (see Fig. 3). Openings 75 in the central lower front portion of wall 11 of the dryer cabinet permits the removable insertion into the dryer of a condenser or heat exchanger structure. An opening 78 provided in the lower portion of cabinet rear wall 14 registers with an opening 79 provided in the lower portion of the inner casing wall 21 (see Figs. 2 and 3). These openings 78 and 79 form an air inlet passage leading from outside the clothes dryer into the lower portion of the cabinet intermediate the inner and outer casings thereof. While I have shown this air inlet passage in the back portion of the dryer cabinet, it is to be understood that cap member 71 could, if desired, be omitted so as to cause outside air to be drawn by fan 74 into the space between the inner and outer cabinet casings from the front side of the cabinet such, for example, as through the louvered opening 76. Thus air may enter the space between the inner and outer casings of the present clothes dryer cabinet through either or both the back and front sides of the cabinet without departing from the spirit of the present invention.

The heat exchanger in the present disclosure is generally represented by the reference character 81 and comprises a plurality of vertical metal tubes 82 interlocked together by a plurality of vertically spaced apart horizontally disposed metal fins 83 (see Fig. 6). The bottom plate 84 of heat exchanger 81 has its sides bent down to provide supporting legs 86 which rest on the cabinet base 12 (see Figs. 2, 6 and 7). The upper plate or fin 87 of heat exchanger 81 has its side edges bent or flanged upwardly and outwardly at an angle as at 88 (see Fig. 6) so as to fit snugly against the side walls of opening 31 in the U-shaped inner casing wall 22 (see Fig. 2). The angled flanges 88 fitting against or overlapping the side walls of opening 31, from the front to the rear thereof,

tend to close the opening and in addition serve to hold or maintain the heat exchanger 81 in a centralized position within the dryer cabinet. The one or left-hand supporting leg 86 of heat exchanger 81 as viewed in Fig. 2 of the drawings is provided with a longitudinal row of holes 92 (see Fig. 6) adjacent the top of leg 86. A pair of angularly disposed ledges 96 and 97 (see Figs. 2, 6 and 7) are secured to the underside of the U-shaped bottom plate 84 of heat exchanger 81 and receive a tray 101 having a pair of brackets 102 welded or otherwise secured to its bottom wall. The one ledge 97 is provided with a longitudinal row of holes 98 (see Figs. 6 and 7) located above the top rim of tray 101. The purpose of holes 91 and 98 will become apparent hereinafter. Each of the brackets 102 have two leg portions, the feet of which are welded or otherwise suitably secured to a pan or receptacle 103. Tray 101 permits water to accumulate therein and may have several small holes (not shown) provided in its bottom so that water will drip therefrom into the water collecting pan or receptacle 103.

The heat exchanger 81 is provided with a front plate 106 (see Figs. 4, 5 and 6) which normally abuts against the front wall of opening 31 to prevent air from escaping through the opening 31 into the space between the cabinet front wall 11 and the inner casing. A bracket 107 secured to plate 106 on heat exchanger 81 supports a front cover 108 which normally closes the upper portion of opening 75 in the cabinet front wall 11 located between the louvered members 76 and 77 (see Figs. 3, 4, 5 and 6). The pan or receptacle 103 is also provided with a front plate 109 (see Figs. 4 and 5) which abuts against the front portion of heat exchanger 81 to close the space between the front of heat exchanger 81 and the base 12. Bracket 111 secured to plate 109, on receptacle 103, supports a front cover 112 which normally lies in vertical alignment with cover 108 to close the lower portion of opening 75 in the cabinet front wall. The front cover 112 is provided with a knob or finger grip 114 for a purpose to be hereinafter described.

In the present arrangement, both the heat exchanger 81 and the receptacle 103 together with the shallow tray 101 are slidable relative to the cabinet and are removable therefrom. Should it be desirable to remove receptacle 103 and tray 101 from the cabinet, finger grip or knob 114 is grasped by the hand and an outward force applied thereto causes receptacle 103, and consequently tray 101 secured thereto, to slide outwardly of opening 75 in the cabinet front wall 11 as shown in Fig. 5 of the drawings. Any accumulation of lint and water in receptacle 103 and tray 101 can be emptied therefrom and the receptacle and tray may then be moved back into the cabinet. Should it be desirable to remove the heat exchanger or condenser 81 from the cabinet, which is usually carried out after the receptacle 103 and tray 101 has been removed, the lower portion of front cover 108 is grasped by the hand and an outward force applied thereto causes the legs 86 on the condenser or the heat exchanger 81 to slide along the cabinet base as is illustrated in Fig. 6 of the drawings to move the unit 81 outwardly of the cabinet through the opening 75. Lint, etc., can be removed from the condenser unit 81 after which it may be slid back into the cabinet.

In the present apparatus two separated air streams are induced into the dryer cabinet one of which is heated in circulating over the heaters 61 and 62 and over the clothes drum into contact with damp clothes to be dried and is then directed through tubes 82 of the heat exchanger or condenser 81 located in the cabinet. The other air stream, which is of considerably greater volume than the heated air stream, is directed over tubes 82 and fins 83 of the heat exchanger 81 for cooling and condensing moisture out of the heated moisture-laden drying air. Both of these streams of air are mixed together within the dryer cabinet prior to being discharged there-

from. For the sake of clearness the first mentioned air stream will hereinafter be referred to as "drying air" while the second mentioned air stream will be referred to as "cooling air." While I have shown electric heaters for heating the incoming drying air stream flowing thereover or for heating the fabrics or fabric containing drum by radiant heat, it is to be understood that any suitable or desirable means may be employed for supplying or imparting heat to the damp fabrics to cause moisture to be released therefrom. In either instance air flowing over the heated fabric containing drum or over heated damp fabrics is heated and absorbs moisture released from the fabrics which moisture is to be removed from the heated moist air prior to its discharge from the cabinet.

After damp clothes or other fabric articles are placed into the perforated container or drum, a suitable or conventional time or chronometric switch (not shown) is actuated and set for a predetermined time of operation of the clothes dryer. The setting of this switch automatically winds the spring of the timing or chronometric means thereof and the switch simultaneously energizes the electric heaters 61 and 62, the motor 58 and the ozone producing lamp 47. The illuminating lamp 46 is preferably in a separate electric circuit energized at 25 will by a conventional manually operating snap switch (not shown). When motor 58 is rendered operative, its shaft upon which fan 74 is mounted rotates and consequently the shaft extension 57 is also rotated. Operation of blower or fan 74 draws drying air into the stationary inner casing of the dryer cabinet through inlet opening 65 and holes 60. The blower or fan 74 simultaneously draws cooling air into the space between the inner and the outer stationary casing through the inlet openings 78 and 79. Thus two separate air streams enter the dryer cabinet at widely spaced apart points. It being understood, of course, that fan 74 by discharging air from the dryer cabinet through the louvered opening 77 creates a suction within the cabinet to cause air exteriorly thereof to be drawn therein through the air inlet openings 78, 79 and 60, 65. The stream of air entering the inner casing of the dryer cabinet flows over and around the deflectors 63 of the electric heaters 61 and 62 and into contact with the hot clothes drum where it is heated. This heated stream of drying air, at approximately 190°, circulates over and into contact with the damp clothes in the clothes container or drum, which is rotated, by the belt and pulley connections 51, 52, 53, 54, 55 and 56 with the motor shaft 57, during circulation of air into and out of the cabinet. Clothes within the rotating clothes drum are agitated and tumbled by the vanes or drag members 39 while the heated stream of drying air circulates thereover and out of the clothes drum through perforations 36 in its cylindrical wall 34. In circulating over the damp clothes, the heated drying air absorbs or picks up moisture released from the clothes or fabrics. The moisture-laden drying air flows out of the inner stationary casing of the dryer cabinet by way of the opening 31 in the bottom thereof and enters passageways of heat exchanger 81 afforded by the tubes 82 thereof. By momentarily breaking up the stream of heated drying air into a plurality of smaller streams as is the case when this air enters tubes 82 of the heat exchanger 81, the heated moist air can be more efficiently and quickly cooled. Simultaneously with the circulation of the heated drying air a separate stream of cooling air of considerable greater volume enters the cabinet by way of openings 78 and 79 and flows over and in contact with the tubes 82 and fins 83 of the heat exchanger 81. This stream of cooling air, being at room temperature of approximately 70°, cools the moisture-laden heated drying air passing through the passageways afforded by tubes 82 of heat exchanger 81 and causes moisture, absorbed from the heated damp clothes and carried therewith, to condense out of the heated moist air. 70

This condensate flows down along the inner surface of tubes 82 of the heat exchanger 81 and drips into the tray 101. Tray 101 is designed to hold a shallow body of condensate water and excess water may overflow the tray 101 or may pass through suitable openings therein as previously described into the drain pan or receptacle 103 where it is collected. The shallow body of condensate water in tray 101 and the body of collected water in pan 103 are indicated in Figs. 5 and 7 of the drawings by the reference numerals 117 and 118 respectively.

The heated drying air passing through the tubes 82 of heat exchanger 81 flows horizontally across the surface of the shallow body of water 117 in tray 101 in a direction toward and thence through holes 98 in the one ledge 97. Thereafter the heated air flows in an opposite horizontal direction across the surface of the body of condensate water 118 collected in receptacle 103 and thence through the outlet holes 92 (see Figs. 2 and 7). By cooling the heated moisture-laden air in the heat exchanger 81, changing its direction of flow and causing it to sweep in opposite directions across the surface of the body of condensate water 117 and 118, any lint picked up from the clothes and circulated with the drying air will be removed therefrom. The lint will be deposited on the inner surface of tubes 82 of heat exchanger 81 and in or on the body of condensate water in tray 101 and pan 103. A structure as shown and described provides an effective and improved lint removing and catching or trapping device for clothes dryers and reduces to a minimum the amount of lint discharged into the room or basement from a clothes dryer cabinet.

After the drying air passes out of or beyond the heat exchanger 81 and the elements therebelow, it is mixed with the cooling air, in the chamber formed by the baffle 67 and its leg 69, prior to being discharged as a single stream of air from the clothes dryer cabinet by fan 74. This mixing of the heated air stream with the cooling air stream within the dryer cabinet materially reduces the temperature of air egressing from the clothes dryer cabinet. Since moisture is efficiently condensed and removed from the heated air by the cooling effect of the greater volume of cooling air, the mixed air stream discharged from the clothes dryer cabinet will not materially increase the humidity within the room or basement in which the cabinet is located.

From the foregoing, it should be apparent that I have provided an improved method of and apparatus for drying damp fabrics, clothes, and other articles. By breaking the heated moisture-laden air stream into a plurality of smaller air streams and passing them through separate passageways of the heat exchanger and by circulating a cooling stream of air of greater volume than the heated air stream over the heat exchanger, moisture is effectively removed from the heated drying air within the cabinet to substantially reduce the moisture content of air discharged from the clothes drying apparatus. The present apparatus eliminates the necessity of extending water pipe lines or the like to the cabinet as would be required if a water-cooled condenser were employed. I obtain the simultaneous circulation of two separate air streams into the cabinet and the discharge of a single mixed air stream from the cabinet by utilizing a single blower or fan operated by a motor which also ordinarily rotates the clothes drum. The apparatus is simple in construction, can be manufactured at low cost and installed without special plumbing or the like pipe connections.

While the form of embodiment of the invention as herein disclosed, constitutes a preferred form, it is to be understood that other forms might be adopted, as may come within the scope of the claim which follows.

What is claimed is as follows:

A dryer comprising: an outer rectangular casing provided with a front panel having a front door opening having an inward cylindrical flange and with a front door

hinged to said panel; a cylindrical drum within said casing supported and driven by a hollow shaft on the rear wall of said casing and having a forwardly directed cylindrical flanged opening telescoping outside said inward cylindrical flange and terminating rearwardly of said door opening; roller supports at the front of said drum within said casing and surrounding said inward and forwardly directed flanged opening; an electric heater outside said drum in an upper corner of said casing; electric illuminating and ozone producing means within said drum; and a support

for said electric illuminating and ozone producing means passing along said hollow shaft.
